MANUFACTURING COMPANY, A CORPORATION OF NEW JERSEY.

BUTTONHOLE CUTTING AND STITCHING MACHINE.

1,135,933.

Specification of Letters Patent. Patented Apr. 13, 1915.

Application filed June 30, 1913. Serial No. 773,505.

To all whom it may concern:

Be it known that I, EDWARD B. ALLEN, a citizen of the United States, residing at Bridgeport, in the county of Fairfield and 5 State of Connecticut, have invented certain new and useful Improvements in Button-hole Cutting and Stitching Machines, of which the following is a specification, reference being had therein to the accompanying 10 drawings.

This invention relates more particularly to buttonhole stitching machines adapted for producing both eyelet-ended and straight buttonholes in cloth garments such 15 as men's coats; and it has for its object to facilitate changes of cutting and stitching conditions whereby either style of button-hole stitching may be produced at will.

As preferably constructed, the machine 20 contains cutting mechanism comprising a cutter-carrying lever upon which are mounted an eyelet-ended cutting blade and a straight cutting blade each adapted to assume an operative position in register with 25 an opposed cutting element. The work-holder receives traveling and side-shift movements relatively to the stitch-forming mechanism through connections with the usual feed-cam, one of said connections comprising a side-shift lever carrying a cam-follower adapted to be locked either in operative relation with the cam-track of the feed-cam for production of the usual side-shift movements or with a fixed cam-track 30 35 for preventing lateral movement of the work-holder while permitting longitudinal traveling or feeding movements thereof.

In the accompanying drawings, Figure 1 is a rear side elevation of the lower portion 40 of a buttonhole cutting and stitching machine constructed in substantial accordance with that of my pending application Serial No. 752,257, filed March 6, 1913, and Fig. 2 a plan of the same. Fig. 3 is a transverse 45 section of the lower portion of the machine base with a portion of the starting mechanism. Fig. 4 is a front side elevation of a portion of the machine including the cutter-controlling and stop-motion devices. Fig. 5 is a perspective view of the feeding mechanism and a portion of its controlling means. Fig. 6 is a side elevation of the cutting device. Fig. 7 a plan of one of the cutter-carrying levers, and Fig. 8 an end view, 50 upon a larger scale, of the slide-block carry-

ing the interchangeable cutting elements. Fig. 9 is an enlarged detail view, partly in section, representing a portion of the feed-cam and the follower carried by said shift-lever. Fig. 10 is an edge view of a portion 60 of the controlling means of the feed-cam actuating device.

The machine is shown constructed with the hollow rectangular base 1 whose top affords the bed-plate 2 from which rises the 65 bracket-arm standard 3. Mounted within and longitudinally of the base is the main-shaft 4 having suitable operative connections with the reciprocating and laterally jogging needle-clamp 5 in which is secured 70 the eye-pointed needle 6 coöperating in the production of overseam stitches with the oscillating loopers 7 and 8 and the loop-detainer 9 arranged below the bed-plate and also operatively connected with the main-shaft. The stitch-forming mechanism thus 75 constituted is of that type in which both the jogging needle and the loop-taking means are mounted upon rotary supports whereby they are caused to perform a semi-rotation 80 in the stitching of the eyelet-end of a buttonhole.

As represented, the feeding mechanism comprises an actuating cam 10 fixed upon the main-shaft and imparting vibratory 85 movements to a lever 11 which are transmitted by suitable means to clutch-dogs 12 embracing the depending flange 13' of the cam-wheel 13 which is provided in its upper face with the feed-cam groove 14 and side-shift groove 15 and upon its periphery with the series of ratchet-teeth 16 extending 90 throughout the greater portion of its circumference with the ends separated by a smooth portion 17.

The feed-cam groove 14 is entered by the roller-stud 18 depending from the lever 19 having one end fulcrumed by means of the stud-screw 20 upon the under side of the bed-plate and carrying at the opposite end 100 a roller-stud 21 entering a transverse guideway formed in the block 22 secured by means of the screw 23 upon the under side of the plate 24 which is in turn secured to the side bars 25 to form a longitudinally 105 sliding frame confined to suitable guides upon the bed-plate. Within the apertured bearing lugs 26 of the bars 25 is secured the cross rod 27 upon which are fitted the depending lugs 28 of the cross slide-plate 29 110

This plate 29 has upon its lower face a block 30 with longitudinally guideway entered by the stud 31 on one end of the side-shift lever 32 fulcrumed intermediate its ends at 33 and having at its rearward end the boss 34 formed with a central aperture 35 within which is slidably fitted the plunger-pin 36 carrying at its lower end the roller-stud 37 normally entering the side-shift cam-groove 15.

The stem 36' of the plunger-pin extends upwardly through an aperture 38 in the plate 24 and is provided at its upper extremity with the head 39. Secured upon the plate 24 by means of screws 40 is a cam-plate 41 formed with a straight slot 42 in register with the aperture 38 and adapted to fit the opposite sides of the reduced intermediate portion 43 of the plunger-pin when raised, as represented in Fig. 9. Overlying the plate 41 at one side of the cam-slot 42 is the latch-plate 44 confined in position thereon by means of the screw-studs 45 passing through transverse slots 46 therein to permit movement of the latch-plate transversely of the slot 42. A spring 47 secured in position by one of the screws 40 serves to press the latch-plate toward the slot 42 to cause its overhanging edge to enter the groove 48 immediately above the portion 43 of the plunger-pin (Fig. 9).

The relative diameters of the parts 36' and 43, is such that, when the plunger-pin is locked in elevated position by the latch-plate 44, as represented in full lines in Fig. 9, the part 43 is closely embraced by the cam-slot 42 by means of which the side-shift lever 32 is held against lateral movement while the slide-frame with the plate 24 is permitted to perform its regular longitudinal feeding movements, while after retraction of the latch-plate the plunger-pin is permitted to descend for entrance of its roller-stud 37 within the cam-groove or track 15, as represented in dotted lines in Fig. 9, sufficient clearance is afforded between the stem 36' of the plunger-pin and the edges of the cam-slot 42 to permit the lateral movement of the plunger-pin under the action of the cam for production of the vibratory or side-shift movements of the lever 32. The plunger-pin, which constitutes a follower for both cam-tracks 15 and 42, is normally maintained in its lower position by gravity, but is locked against displacement from operative relation with the actuating cam-track by means of the latch-plate 44 which overhangs the upper extremity of that portion of the enlargement 43 of the plunger-pin above the groove 48.

Resting upon and movable with the slide-plate 29 are two clamp-plates 49 mounted thereon for reciprocal edgewise movement and affording the lower jaws of the work-holder whose upper jaws are afforded by

clamping feet 50 carried by spring-arms 51 which are in practice sustained independently by the clamp-plates 49.

Fitted to suitable longitudinal ways within an opening in the bed-plate is the base-plate 52 formed with the spaced bearing lugs 53 sustaining the fulcrum-pin 54 upon which are mounted the hubs of the upper and lower cutter-levers 55 and 56 whose rearward ends embrace the transverse cut-

ter-actuating shaft 57 carrying the cutter-lever actuating cam projections 57' and 57". The cutter-shaft carries the cam-disk 58 provided in one face with a cam-groove 58' entered by a stud 59' upon the link member 59 pivotally connected with a rearward extension 58' of one of the lugs 53, through which link the cutter-levers derive from the cam 58 traveling movements toward and from cutting position. The upper cutter-

lever carries at its forward or operative end the adjustable and removable smooth faced cutter-block 60, and the lower cutter-lever 56 is formed at its outer end with the transverse head 61 provided with the transverse undercut channel 62 in which is fitted the cutter-carrying slide-plate 63. The plate 63 is formed upon opposite edges with flanges 64 one of which is provided with the spaced notches 65 adapted to be entered by the

downturned latch-tooth 66 of a slide-bar 67 mounted within a channelway in the side of the cutter-lever 56 in which it is confined by means of the strap 68. The slide-bar 67 has at its rearward end the lug 69 between which and the shoulder of the lever 56 is interposed the spring 70 to normally maintain the latch-tooth 66 in one of the notches 65, the lug 69 having secured thereto an upwardly extending finger-piece 71 by

means of which the slide-bar 67 may be retracted to permit the cutter slide-plate 63 to be shifted.

The slide-plate 63 has removably and adjustably secured thereto the spaced cutters 72 and 73, having at the rearward ends the pear-shaped cutting portions 72' and 73' of different sizes, and the intermediate straight cutting blade 74. The cutter 72 72' having the larger eyelet end is designed for cutting eyelet-ended buttonholes preparatory to stitching, and that having the smaller eyelet end is designed for cutting similar buttonholes subsequent to stitching, while the shorter straight bladed cutter 74 is designed for cutting a straight buttonhole slit. By retraction of the latch tooth 66, the cutter-plate 63 may be shifted so as to bring any one of these cutters into register with the cutter-block 60 constituting the upper cutting element, thereby adapting the machine for cutting buttonholes of different shapes or styles by a mere adjustment of the cutter-plate.

The cutter-shaft 57 carries the loose con-

tinuously running belt-wheel 75 formed upon its inner face with an annular flange 76 having spaced radial notches 77 adapted to be entered by a coupling tooth 78 upon the slide-block 79 mounted in a suitable radial guideway of the disk 80 fixed upon the cutter-shaft 57. The tooth 78 is engaged by the arm 81 of a spring carried by the disk 80 for pressing the tooth outwardly into coupling relation with the belt-wheel.

The slide-block is held normally retracted by engagement of the lug 82 on the opposite face thereof by the cam-shaped edge 83 of the flange 84 upon the free end of the lever 85 fulcrumed upon the stud-screw 86. The temporary retraction of the lever 85 for release of the lug 82 permits the coupling of the belt-wheel and disk 80 to produce a rotation of the cutter-shaft which is arrested at completion thereof by reengagement of the lug 82 with the cam edge of the flange 84.

As shown and described in my said application, the hub 87 of the continuously running loose belt-wheel 88 upon the main-shaft is formed with an eccentric embraced by the strap 89 connected by the link 90 with a lateral arm 91 of a rock-shaft 92 provided with the upwardly extending crank-arms 93 and 94. To the crank-arm 93 is pivotally attached one end of the pawl-lever 95 which, with the primary and auxiliary holding pawls 96 and 97 acting upon the rack 98, serves to impart endwise step-by-step operative movements to the push-bar 99 carrying the block 100 which is normally maintained in engagement with the head 101 of the adjustable stop-bar 102 by means of the spring 103.

When the machine is at rest, the work-holder is disposed in cutting position at the extreme rearward end of its traverse and out of register with the stitch-forming mechanism, and preparatory to a stitching operation the feed-wheel receives a partial rotation to bring the work-holder into register with the stitch-forming mechanism. This is effected through the engagement of the peripheral ratchet teeth 16 by a spring-pressed pawl 104 (Fig. 1) carried by the push-bar 99, the extent of such initial movement being determined by the initial position of the bar 99 which is in turn determined by the position of the stop-member 101.

The pawls 95, 96 and 97 are normally held lifted above the rack 98 by engagement of the hook 96' of the primary holding pawl with a lateral lip 105 at the upper end of the upwardly extending arm 106 of an elbow-lever fulcrumed at 107 and provided with the lateral arm 108 resting upon the face of the forked block 109 of the starting bar 110 journaled in the machine base. The cutter-shaft carries the cam 111 which,

near the completion of a rotation, acts upon a spring-held extension 112 of the arm 106 by means of which the latter is disengaged from the holding pawl and an operative movement is thus imparted to the push-bar 99 which is communicated to the work-holder through the feed-cam, the disengagement of the actuating pawl from the rack-bar 98 being automatically effected at the completion of such movement.

The depending rearward extension 99' of the push-bar carries the tripping stud 113 which engages the depending arm 114 of the rock-shaft 115 sustaining the tilting stop-lever 116, and the tilting of said stop-lever 80 disengages the tooth 117 upon the spring-pressed slide-block 118 carried by said lever from the clutch member 119 to cause the coupling of the belt-wheel 88 with the main-shaft and consequent operation of the stitch-forming mechanism and normal actuation of the feed-cam wheel in spacing the stitches and producing the side-shaft movements of the work.

The slide-block 118 has, as represented in Fig. 5, a detachable connection with the plural-armed lever 120 pivotally mounted upon the hanger 121 sustained by the bed-plate and having a lateral arm formed with a bearing lip 122 normally sustained by means of the spring 123 in engagement with the inner face of the pawl-bar 124 connected at its rearward end with the rock-shaft arm 94 and having at its forward end the toothed-extremity 125 adapted for engagement with the peripheral teeth 16 of the feed-cam wheel. When the slide-block 118 descends in the action of the stop-motion to arrest the stitch-forming mechanism, a bearing lip 126 of another arm of the rock-lever 120 thrusts the pawl-bar 124 into operative relation with the periphery of the feed-cam wheel, thereby continuing its movement until the operative portion 125 arrives at the smooth section 17, the cam-wheel having 110 performed a complete rotation and the work-holder having thus been returned to initial cutting position.

The stop-lever 116 has at its upper end the lateral arm 116' adapted for engagement by the hooked extremity 127 of the detent-lever 128 fulcrumed at 129 and provided at its opposite end with the inclined nose 130. Secured upon the traveling plate 24 is a block 131 upon which is adjustably secured by means of the fastening screw 132 passing through the slot 133 the bar 134 carrying the fulcrum-stud 135 upon which is mounted the tripping dog 136 yieldingly maintained in normal upright position by means of a spring 137 with a stop-shoulder thereon resting upon the bar 134. In the longitudinal travel of the slide-frame 24 25, the engagement of the dog 136 with an abrupt shoulder upon the lower edge of the 130

detent-lever 128 causes the dog to tilt without shifting such lever in opposition to its spring 138; but upon the return of the slide-frame, the engagement of the inclined upper end of the now rigid tripping dog 136 with the extremity 130 of the detent-lever causes the tilting of the latter and release of the stop-lever 116, which, under the action of its spring 116' moves to stopping 10 position.

As represented more particularly in Fig. 3, the starting bar has fixed thereon intermediate its ends a thrust-collar 139 adapted for engagement with the upwardly extending arm 140 of an elbow-lever fulcrumed upon the stud-screw 141 and provided with the lateral arm 142 connected by a cord or chain 143 with actuating means such as a knee-lever or treadle acting in 15 position to the spring 144. Fixed upon the forward end of the bar 110 is a tripping member formed with the angularly arranged arms 145, 146 and 147. The arm 145 is adapted for engagement with an extension 84' of the flange 84 of lever 85, while the rounded upper extremity of the arm 146 is adapted to engage the under face of a lateral extension 148 of the trip-lever 149 fulcrumed upon the stud 150 to lift it out of 20 operative relation with the tripping stud 151 carried by the feed-wheel. The forked rearwardly extending arm of this trip-lever 25 embraces the extension 84' of the flange 84.

The arm 147 carries the spring-pressed 30 pin 152 adapted, when the tripping member is in either the full line or dotted line position of Fig. 4, to enter one of two apertures 153 of the base 1 to maintain the bar 110 in the required position of adjustment. In the 35 full line position of the parts, represented in the drawings, the shifting of the starting bar 110 obviously causes the initial rotation of the cutter-shaft and actuation of the cutter followed by the travel of the work-holder 40 to stitching position and the stitching of the buttonhole which is succeeded by the return of the work-holder to initial position, a second actuation of the cutter being prevented by the displacement of the trip-lever 149 from the path of movement 45 of the tripping stud 151. When the tripping member 145, 146, 147 is turned into the dotted line position of Fig. 4, the arms 145 and 146 assume positions out of operative 50 relation with the parts 84' and 149, and when the starting bar is actuated a rocking cam-plate 154 mounted in the block 109 is caused to first tilt the elbow-lever 106, 108 to set the push-bar actuating means in 55 operation and thereafter lock such elbow-lever from a second actuation during the same cycle, the work-holder being first moved 60 from cutting into stitching position, the stitching performed, the work-holder re-stitching performed, the work-holder re-turned to cutting position and the cutting 65

mechanism finally tripped into operation by engagement of the tripping stud 151 with the trip-lever 149 to cause the cutting of the buttonhole subsequent to stitching. With these different adjustments to determine the order of operation of the cutting and stitching mechanism, the appropriate cutting elements 72 and 73 are set in register with the cutter-block 60.

When a straight buttonhole is to be produced, for instance upon the lapel of a coat, the straight cutting blade 74 is shifted into register with the cutter-block 60 and the plunger-pin 36, which is normally in its lower position and in operative relation with the side-shift cam-track 15, is retracted to bring its reduced portion 43 within the slot 42 affording a stationary cam-track, and the cutting and stitching mechanisms set in operation in either order, thereby effecting the cutting and stitching of a straight button-hole with one end reinforced by radially laid stitches. In this adjustment of the feeding mechanism the work-holder is restrained against lateral movement, and is 90 confined to movements in opposite directions lengthwise of the buttonhole slit.

In the machine shown and described in my prior application Serial No. 752,257, the needle is mounted in such manner that it is 95 at the same side of the axis of rotation of the needle-bar in both its edge-stitch and depth-stitch position; but in the machine as shown and described herein, the needle is sustained concentrically with the needle-bar 100 in its edge-stitch position in order that its edge stitch thrusts in working either the sides or ends of buttonholes may be in alignment with the straight slit. It is obvious, however, that the nature of the stationary 105 cam-track 42 will be determined by the character of the machine in which the present improvement is embodied.

Other means within the scope of the present invention will readily suggest themselves 110 for controlling the lateral positions of the work-holder in changing from eyelet-end buttonholes to straight buttonholes through the shift-lever or otherwise, the characteristic features of the present invention being 115 the provision upon one of the cutter-carrying members of a plurality of interchangeable cutting elements in connection with means for conforming the feeding movements of the work-holder with the contour 120 of the style of cutter selected, and the provision of means of adjustment within the machine whereby the feed may be varied to change the style of the buttonhole stitching.

In order that a buttonhole machine may 125 be convertible for production of either eyelet-end buttonholes or straight buttonholes, it is necessary to provide not only means for imparting relative side-shift movements between the overseam stitch-forming mecha- 130

nism and the work for producing the enlargement at the eyelet-end, but to provide means of some kind whereby the working position of the stitch-forming mechanism 5 may be shifted relatively to the work-holder across a median line coincident with the buttonhole slit for the stitching of the opposite edges of the buttonhole. In the present instance, the mechanism for imparting to 10 the stitch-forming mechanism a semi-rotation for the eyelet stitching operation constitutes the means whereby the stitch-forming mechanism is caused to operate successively upon opposite sides of the button-hole slit, and the side-shift means connected with the work-holder is that which imparts relative sidewise movements between the stitch-forming mechanism and the work in stitching the initial and final portions of 15 20 the eyelet. In the construction herein shown and described, one of these side shift means has provision whereby it may be rendered either effective or ineffective.

Having thus set forth the nature of the 25 invention, what I claim herein is:—

1. In a buttonhole sewing machine, in combination, stitch-forming mechanism, a work-holder, cutting mechanism comprising a cutter-carrier and a plurality of cutting 30 elements of different shapes mounted thereon, and feeding mechanism for producing between the stitch-forming mechanism and the work-holder relative traveling or feeding movements and side-shift movements, 35 and comprising adjustable means whereby the relative movements between the stitch-forming mechanism and the work-holder are caused to conform with the contours of said cutting elements. 40 2. In a buttonhole sewing machine, in combination, stitch-forming and feeding mechanisms, cutting mechanism comprising a cutter-carrier and interchangeable cutting elements mounted thereon, and feed-changing 45 means adjustable to vary the feed of the work in conformity with the contours of the respective cutting elements.

3. In a buttonhole sewing machine, in combination, stitch-forming mechanism, cutting mechanism comprising a cutter-carrier and interchangeable cutting elements of different shapes mounted thereon, and feeding mechanism comprising an actuating member and an adjustable element adapted to 50 55 assume relative to said member different positions corresponding with the respective cutting elements.

4. In a buttonhole sewing machine, in combination, overseam stitch-forming mechanism turning means therefor, a work-holder, and feeding mechanism for producing relative movements between the stitch-forming mechanism and the work-holder and comprising means for producing feeding 60 65 movements lengthwise of the buttonhole,

means for producing side-shift movements crosswise of the buttonhole, actuating means, and means whereby said actuating means are maintained wholly ineffective in producing side-shift movements throughout a complete 70 stitching cycle. 75

5. In a buttonhole sewing machine, in combination, overseam stitch-forming mechanism, a work-holder, means connected with the stitch-forming mechanism and acting at intervals embracing a plurality of overseam-stitch forming cycles whereby the working position of the stitch-forming mechanism is shifted relatively to the work-holder from one to the other side of a median line parallel with the direction of feed, and feeding mechanism for producing relative movements between the stitch-forming mechanism and the work-holder and comprising means for producing feeding movements 80 lengthwise of the buttonhole, means for producing side-shift movements crosswise of the buttonhole and including a laterally movable element, actuating means from which exclusively said side-shift movements 85 are derived, and means carried by said element whereby it is caused to remain disconnected from its actuating means for interruption of the side-shift movements throughout a complete stitching cycle. 90 95

6. In a buttonhole sewing machine, in combination, stitch-forming mechanism, a work-holder, and feeding mechanism for producing relative movements between the stitch-forming mechanism and the work-holder and comprising means for producing feeding movements lengthwise of the buttonhole and side-shift movements including a laterally movable element carrying a cam-follower, an actuating cam containing a cam-track for engagement by said follower, and means for locking said cam-follower within or out of operative relation with said cam-track during a complete feeding cycle. 100 105

7. In a buttonhole sewing machine, in combination, stitch-forming mechanism, a work-holder, and feeding mechanism for producing relative movements between the stitch-forming mechanism and the work-holder and comprising means for producing feeding movements lengthwise of the buttonhole and side-shift movements including a laterally movable element carrying a cam-follower, an actuating cam containing a cam-track for engagement by said follower, and means sustained independently of said laterally movable element for locking said cam-follower within or out of operative relation with said cam-track during a complete feeding cycle. 110 115 120 125

8. In a buttonhole sewing machine, in combination, stitch-forming mechanism, a work-holder, and feeding mechanism for producing relative movements between the stitch-forming mechanism and the work- 130

holder and comprising means for producing feeding movements lengthwise of the buttonhole and side-shift movements including a laterally movable element carrying a cam-follower, an actuating cam containing a cam-track for engagement by said follower, a cam-track sustained independently of said actuating cam, and means for maintaining said cam-follower in operative relation with either of said cam-tracks.

9. In a buttonhole sewing machine, in combination, stitch-forming mechanism, a work-holder, and feeding mechanism for producing relative movements between the stitch-forming mechanism and the work-holder and comprising means for producing feeding movements lengthwise of the buttonhole and side-shift movements including a laterally movable element carrying a cam-follower, an actuating cam containing a cam-track for engagement by said follower, a cam-track sustained by a stationary support, and means for maintaining said cam-follower in operative relation with either of said cam-tracks.

10. In a buttonhole sewing machine, in combination, stitch-forming mechanism, cutting mechanism comprising a cutter-carrier and interchangeable cutting elements of different shapes and lengths mounted thereon, and feeding mechanism comprising means for producing relative work-advancing or feeding movements and side-shift move-

ments between the stitch-forming mechanism and the work, means for varying the length of relative travel between the stitch-forming mechanism and the work, and adjustable means for controlling said side-shift movements.

11. In a buttonhole sewing machine, in combination, stitch-forming mechanism, cutting mechanism comprising a cutting element, a cutter-carrier, a plurality of eyelet-ended cutting elements and a straight-bladed cutting element mounted upon said carrier and each adapted to assume a position in operative relation with the first-named cutting element, feeding mechanism comprising means for producing relative work-advancing or feeding movements and side-shift movements between the stitch-forming mechanism and the work, means for varying the length of relative travel between the stitch-forming mechanism and the work and adjustable means for controlling said side-shift movements, and adjustable means whereby the order of operation of the stitch-forming and cutting mechanisms may be determined.

In testimony whereof, I have signed my name to this specification, in the presence of two subscribing witnesses.

EDWARD B. ALLEN.
